UNITED STATES PATENT OFFICE.

OWEN DAVID LUCAS, OF LONDON, ENGLAND, ASSIGNOR TO VICKERS LIMITED, OF BROADWAY, WESTMINSTER, ENGLAND, A BRITISH COMPANY.

RETORT FURNACE.

Application filed March 31, 1924. Serial No. 703,309.

To all whom it may concern:

Be it known that I, OWEN DAVID LUCAS, a subject of the King of Great Britain, residing at 49 Linden Gardens, London, W., England, have invented certain new and useful Improvements in Retort Furnaces, of which the following is a specification.

This invention relates to an improved kiln or retort furnace of the horizontal rotary type. Previously it has been proposed in retorts of this type to use a cylinder mounted with its axis approximately horizontal and adapted to be rotated, the heat necessary for the distillation of the material to be treated being obtained either by internal combustion or by externally heating the retort. In the first case, constructional difficulties are not serious, but the system has the disadvantage that the products of combustion mix with the products of distillation. In the second case, the size of the retort is limited by the difficulty of making a cylinder sufficiently rigid as not to distort under heat, and at the same time sufficiently thin to transmit the external heat to the interior.

According to the present invention there is employed an external heat insulated cylinder mounted with its axis horizontal or approximately so and an inner cylinder mounted axially within the outer one so as to leave an annular space. This inner cylinder is supported and carried by the outer cylinder, and the supports may be fitted axially for its whole length or circumferentially at intervals. The heat is applied to the annular space between the two cylinders, the whole system rotating as one unit.

The outer cylinder may terminate at one end in a moderately close-fitting and non-rotary casing which contains the heat producing apparatus which may be in the form of gas burners (with or without compressed air), oil burners, pulverized fuel burners or the like. The combustion system is arranged so that the flame is projected into the annular space between the two cylinders and the inner cylinder may be protected for a short portion of its length at the combustion casing end by suitable refractory material forming a non-rotating part of the system.

Instead of the combustion taking place at one end only the heat may be introduced at intervals over the length of the retort by suitable burners placed outside the main cylinder and rotating with it, these burners

being connected to axial supply pipes at the ends of the retort, for gas or other combustible material and air.

In order that the said invention may be clearly understood and readily carried into effect, the same will now be described more fully with reference to the accompanying drawings, in which:

Figure 1 is a vertical axial section of the left hand portion of a retort constructed in accordance with this invention,

Figure 2 is a continuation of Figure 1 showing the right hand portion of the retort, and

Figure 3 is a section taken approximately on the line 3, 3 of Figure 1.

A is the outer cylinder provided with a layer of brickwork or other suitable refractory material and B is the inner cylinder mounted axially within the outer cylinder A with an annular space A¹ between them. The said cylinders are connected together, so as to rotate as one unit, by supports or carriers B¹, B¹ . . . which as shown are arranged radially but which might be arranged longitudinally. At the right hand end of the retort a stationary casing C is provided which projects slightly and with a moderately close fit into the contiguous end of the said outer cylinder. This casing carries the heat producing apparatus comprising burners e, e for projecting flames into the annular space A¹ between the cylinders. These burners may be gas burners (with or without compressed air), oil burners or pulverized fuel burners or the like. Alternatively the flames may, as aforesaid, be introduced at intervals over the length of the outer cylinder A by suitable burners placed outside the said cylinder and rotating with it, the said burners being connected to axial supply pipes for the combustible material, which pipes are situated at one or both ends of the retort. The said casing C has a projecting inner portion C¹ serving to protect the contiguous conical portion of the inner cylinder B, this projecting portion being composed of suitable refractory material. The other end of the outer cylinder A projects into a stationary casing D connected to or constituting the flue or chimney and an air ring d is provided between the cylinder A and the said casing D. The said outer cylinder has a toothed ring A² with which meshes a pinion driven by

- 2
- a suitable prime mover to rotate the unit composed of the outer and inner cylinders, the outer cylinder being supported on suitable rollers α , α as is well understood.
- 5 The inner cylinder B is gradually reduced in diameter at each end to form smaller cylinders b , b^1 projecting through the combustion casing C and through the flue casing D respectively. The said small cylinder b projects through a gland carried by a stationary casing B^2 into which the ash or coke discharges and from which the products of combustion pass through the pipe b^2 . The lower end of this casing B^2 is provided with a hand operated discharge valve b^3 by which the ash or coke is caused to pass from the casing B^2 . The other small cylinder b^1 passes through a gland to a non-rotating hopper feed casing B^3 having an angularly displaceable container B^4 by which the material in the hopper b^4 is caused to pass intermittently into position for being fed into the inner cylinder B by a feed screw B^5 . This feed screw and 25 a discharge screw B^6 at the other end of the retort are mounted on an axial tube B^7 carrying suitable breakers and conveyor's b^7 which, at certain points in the rotation of the tube B^7 , come into contact with the 30 inner surface of the inner cylinder B so as to act as scrapers to prevent the formation of scale on the said inner wall. This tube is connected at each end to the casings B^2 and B^3 so that it remains stationary 35 during the rotation of the cylinders A and B. The said tube is also perforated as shown so that steam admitted to the said tube from a supply pipe B^8 and controlled by a stop valve b^8 can be admitted to the 40 inner cylinder B. The said breakers b^7 are retained in position axially by means of bars B^9 at the ends of the inner cylinder B. The said tube B^7 may also serve to carry pyrometers or other means of ascertaining the internal temperature at various 45 points in the length of the retort.
- It will be observed that the direction of flow of the material through the retort is opposite to that of the travel of the flame 50 and products of combustion from the burners c in the annular space A^1 . When the retort is not arranged horizontally it may be inclined somewhat from the horizontal with the combustion casing end lower than 55 the flue casing end.
- What I claim and desire to secure by Letters Patent of the United States is:—
1. In a retort furnace, the combination of a rotary heat insulated cylinder, a second rotary cylinder mounted within the former cylinder so as to leave an annular space between it and the first-mentioned cylinder, the material to be treated passing through the second cylinder and the heating medium passing through said annular space, a stationary member located within said second cylinder, and breaker and conveyor elements carried by said stationary member. 60
2. In a retort furnace, the combination of a rotary heat insulated cylinder, a second rotary cylinder mounted within the former cylinder so as to leave an annular space between it and the first-mentioned cylinder, the material to be treated passing through the second cylinder and the heating medium passing through said annular space, a stationary member located within said second cylinder, and breaker and conveyor elements carried by said stationary member. 70
3. In a retort furnace, the combination of a rotary heat insulated cylinder, a second rotary cylinder mounted within the former cylinder so as to leave an annular space between it and the first mentioned cylinder, the material to be treated passing through the second cylinder and the heating medium passing through said annular space, a stationary member located within said second cylinder, and breaker and conveyor elements carried by said stationary member, said elements at certain points in 80 the rotation of the cylinders coming into contact with the inner wall of the second cylinder to prevent the formation of scale thereon.
4. In a retort furnace, the combination of a rotary heat insulated cylinder, a second rotary cylinder mounted within the former cylinder so as to leave an annular space between it and the first-mentioned cylinder, the material to be treated passing through the second cylinder and the heating medium passing through said annular space, a stationary perforated tube supplied with steam and located within said second cylinder, and breaker and conveyor elements 90 carried by said tube.
5. In a retort furnace, the combination of a rotary heat insulated cylinder, a second rotary cylinder mounted within the former cylinder so as to leave an annular space between it and the first-mentioned cylinder, the material to be treated passing through the second cylinder and the heating medium passing through said annular space, a stationary perforated tube supplied with steam and located within said second cylinder, and breaker and conveyor elements 95 carried by said tube.
6. In a retort furnace, the combination of a rotary heat insulated cylinder, a second rotary cylinder mounted within the former cylinder so as to leave an annular space between it and the first-mentioned cylinder, the material to be treated passing through the second cylinder and the heating medium passing through said annular space, a stationary perforated tube supplied with steam and located within said second cylinder, and breaker and conveyor elements 100 carried by said tube, said elements at certain points in the rotation of the cylinders coming into contact with the inner wall of the second cylinder to prevent the formation of scale thereon.
7. In a retort furnace, the combination of a rotary heat insulated cylinder, a second rotary cylinder mounted within the former cylinder so as to leave an annular space between it and the first-mentioned cylinder, the material to be treated passing through the second cylinder and the heating medium passing through said annular space, a stationary perforated tube supplied with steam and located within said second cylinder, and breaker and conveyor elements 105 carried by said tube, said elements at certain points in the rotation of the cylinders coming into contact with the inner wall of the second cylinder to prevent the formation of scale thereon.

OWEN DAVID LUCAS.
